(57) **CLAIM**

The ornamental design for a display screen with transitional icon, as shown and described.

DESCRIPTION

FIG. 1 is a front view of a first image in the sequence for a display screen with transitional icon showing our new design; FIG. 2 is a front view of a second image thereof; and, FIG. 3 is a front view of a third image thereof.

The broken lines showing of the display screen is for environmental purposes only and forms no part of the claimed design. The broken lines within the FIGS. 1-3 show portions of the transitional icon which form no part of the claimed design.

The dot-dash broken lines shown in the drawings represent the display screen and form no part of the claimed design. The dash-dot broken lines represent portions of the transitional icon and form no part of the claimed design.

1 Claim, 3 Drawing Sheets
